United States Patent Office

Des. 183,814
Patented Oct. 28, 1958

183,814

RESTAURANT BOOTH

Wilmot H. Scott, St. Louis, Mo., assignor to Vitro Products Co., St. Louis, Mo., a corporation of Missouri

Application April 25, 1957, Serial No. 45,891

Term of patent 7 years

(Cl. D15—11)

FIG. 1.

FIG. 2.

FIG. 3.

FIG. 4.

Fig. 1 is a top plan view of a restaurant booth, showing my new design;

Fig. 2 is a front elevational view thereof;

Fig. 3 is an end elevational view thereof, and

Fig. 4 is a perspective view of the restaurant booth of my invention.

I claim:

The ornamental design for a restaurant booth, substantially as shown.
